DESIGN FOR A LIQUID DISPENSING APPARATUS

William M. Griffin, Fort Wayne, Ind., assignor to Wayne Company, Fort Wayne, Ind., a corporation of Indiana

Application February 8, 1936, Serial No. 61,039

Term of patent 7 years

To all whom it may concern:

Be it known that I, William M. Griffin, a citizen of the United States, residing at Fort Wayne, in the county of Allen and State of Indiana, have invented a new, original, and ornamental Design for Liquid Dispensing Apparatus, of which the following is a specification, reference being had to the accompanying drawing, forming a part thereto.

the liquid dispensing apparatus showing my new design; and

Figure 2 is a perspective elevation of the liquid dispensing apparatus taken from the opposite corner of the device as illustrated in Figure 1.

I claim:

The ornamental design for a liquid dispensing apparatus, as shown.

WILLIAM M. GRIFFIN.
